United States Patent

Des. 237,060
Patented Oct. 7, 1975

237,060

PYROMETER COVER

William E. Engelhard, Owego, N.Y., assignor to Pyro-Serv Instruments, Inc., North Arlington, N.J.

Filed July 19, 1973, Ser. No. 380,613

Term of patent 14 years

Int. Cl. D10—04

U.S. Cl. D10—46

FIG. 1

FIG. 2

FIG. 3

FIG. 4

FIG. 5

FIG. 6

FIG. 1 is a left front perspective view of a cover for pyrometer housing showing my new design;

FIG. 2 is a front elevational view thereof;

FIG. 3 is a left side elevational view thereof, the right side being a mirror image thereto;

FIG. 4 is a top plan view thereof;

FIG. 5 is a rear elevational view thereof; and

FIG. 6 is a bottom view thereof.

I claim:

The ornamental design for a pyrometer cover, substantially as shown and described.
